UNITED STATES PATENT OFFICE.

GEORGE W. McMULLEN, OF CHICAGO, ILLINOIS.

PROCESS OF MAKING SUGAR.

No. 913,758.

Specification of Letters Patent.

Patented March 2, 1909.

Application filed May 4, 1907. Serial No. 371,821.

To all whom it may concern:-

Be it known that I, GEORGE W. McMULLEN, a citizen of the United States, residing at Chicago, in the county of Cook and State of Illinois, have invented certain new and useful Improvements in Processes of Making Sugar, of which the following is a specification.

This invention relates to improvements in the art of making sugar and refers more specifically to an improved process which involves, first, cutting up and drying the sugar-producing plant, then grinding the dried material and finally extracting the sugar from the ground product.

Among the salient objects of the invention are to provide a process whereby the sugar-producing plant may be dried promptly at that time when the material is in prime condition, and in such manner as to preserve the full sugar content, without chemical change or deterioration; to provide a process whereby the sugar may be extracted from the previously dried material in a most efficient manner, by the use of a smaller percentage of water than has heretofore been found necessary and this accomplished more rapidly than has heretofore been the case; to provide a process which in addition to facilitating the extraction of the sugar, also facilitates the drying of the pulp or non-sugar solid residue, thereby so reducing the cost of converting the same into a commercially salable condition that it becomes a valuable by-product; and in general to provide a simple, rapid and economical process of the character referred to.

It is common practice to slice or cut up sugar beets and sometimes sugarcane preparatory to extracting the sugar therefrom by diffusion. In carrying out my process, particularly when dealing with sugar beets, I take the beets as they come from the field and as promptly as practicable cleanse and slice or otherwise suitably cut up the roots. I then dry the same in any suitable or preferred manner which will insure the driving off of the water without effecting any substantial chemical or detrimental change in the sugar content. When properly and fully dried, the slices are quite brittle or friable, so that they may be readily reduced to finely granulated form by means of an ordinary grinding machine.

The next step of the process consists in grinding or otherwise finely granulating the

dried slices, and it is to be noted that this step may be performed immediately after the drying or it may be deferred to any future time; it being noted, however, that the dried material is more or less hygroscopic and therefore if the grinding is deferred for a considerable period of time and the material exposed to atmospheric conditions it may absorb sufficient moisture to render a slight re-drying necessary before grinding.

In grinding the dried slices I prefer to use a grinding machine of such type that it will finely granulate the material rather than reduce it to powder or dust; the object being to secure an extremely finely divided material which is nevertheless readily and freely permeable by water. A certain amount of the dried material will be reduced to powder as an incident to grinding by almost any grinding machine, but the presence of this in the mass will not be a particular objection.

The next step consists in extracting the sugar from the ground material by saturating it with water and thereafter separating the water with the sugar in solution from the solids. In practice I find it preferable to pursue a process of extracting closely analogous to the ordinary diffusion process. That is to say, I preferably first moisten the ground material by adding limited quantities of water thereto and stirring the mixture, so as to prevent it from forming into lumps or masses when subsequently flooded in the diffusion tanks, and I then extract the saccharine liquid by subjecting the moistened mass to the usual diffusion process in a diffusion battery. The sugar is subsequently recovered from the liquid in any usual manner.

By grinding the dried material before extracting, I find that a much less quantity of water is required to effect a practically perfect extraction, the sugar being dissolved out much more readily and rapidly thus giving a heavier solution. The subsequent evaporation of this liquid is, of course, accomplished with a corresponding saving of time and fuel. Moreover, the residue which is left readily and quickly drains out so as to leave a relatively small amount of free water therein, and the subsequent operation of evaporating out the absorbed water is more readily and rapidly accomplished on account of the finely divided condition of the residue. The more rapid extraction and the handling of the relatively smaller amounts

of liquid, of course, means an increased daily capacity of a plant of given size.

I claim as my invention:

1. An improved process of making sugar which consists in first cutting the sugar producing plant into slices or small bodies, next desiccating the cut material into a frangible or brittle condition, then comminuting the desiccated material, then saturating the comminuted material and finally separating the saccharine liquid from the solids and recovering the sugar therefrom.

2. An improved process of making sugar which consists in first cutting the sugar producing plant into slices, next desiccating the cut material into frangible or brittle condition, then grinding the desiccated material into finely granulated form then extracting

the sugar therefrom by diffusion and finally recovering the sugar from the saccharine liquid by evaporation.

3. An improved process of making sugar from beets which consists in first cutting the beets into slices or small bodies, next drying the cut material into frangible or brittle condition, then grinding the desiccated material into granulated form, then preliminarily moistening the ground material, then saturating the mass and dissolving out the sugar, as by percolation or diffusion and finally recovering the sugar from said liquid by evaporation.

GEORGE W. McMULLEN.
